UNITED STATES PATENT OFFICE.

BENJAMIN MORTON, OF FIVE FORKS, LANCASTER COUNTY, PENNSYLVANIA.

COUPLING-LINK.

SPECIFICATION forming part of Letters Patent No. 395,794, dated January 8, 1889.

Application filed October 17, 1888. Serial No. 288,355. (No model.)

To all whom it may concern.

Be it known that I, BENJAMIN MORTON, a citizen of the United States, residing at Five Forks, Pequea township, county of Lancaster, 5 State of Pennsylvania, have invented certain Improvements in Coupling-Links, of which the following is a specification.

This invention relates to that class of links used by farmers to connect the whiffle-tree 10 with implements used in the field—such as plows, harrows, and the like—or to connect the parts of chains used as traces or for similar purposes; and it consists of an ordinary link constructed in two parts, which parts are 15 hinged and held together substantially in the manner and for the purpose hereinafter described and claimed.

Figure 1 is a side view of a link embodying my invention with the hinged portion 20 closed, the connected links being shown in section; Fig. 2, a similar view of the link with the hinged portion partially open; Fig. 3, a side view of the link with the hinged portion 25 opened to its full extent; and Fig. 4, a horizontal section through the link on the line *xx*, Fig. 1.

In the drawings, A represents the main portion or body of the link, having one of its sides open; and B, the hinged portion, formed with 30 a tongue, C, thereon, which is received and pivoted in a recess, *a*, cut in the body A.

E is a pin which passes through a perforation in the tongue and corresponding perforations in the walls of the recess and pivots 35 the part B to the body A of the link. The tongue as it rests in the recess extends entirely around one end of the link into the longitudinal part thereof and embraces and passes under one of the connected links, G. A hasp, 40 *b*, is formed on the outer end of the hinged part B, and when that part is shut down to close the open side of the body A engages a staple, F, on the end of the body opposite to that in which it is pivoted. After the link is 45 closed a suitable pin is inserted in the opening *f* of the staple. By this construction it is impossible under ordinary circumstances for either of the connected links G and H to be

accidentally disconnected from the link, even should the pin inserted in the opening *f* of the staple drop out, the links serving to keep the hinged portion closed, for only by the link H dropping back to the position shown by the dotted lines at I, Fig. 1, and the link II retaining the position it there occupies can 50 the hinged portion B be opened. With the link H in the position I the link G prevents the opening of the part B by its pressure upon the tongue C, while by any simultaneous movement whatever of the links II and 55 G toward the center of the link A B they would prevent the opening of the hinged part B and block the passage of each other outward, so as to relieve the tongue C from their pressure.

The engagement of the hasp over the staple and of the tongue C with the link G makes the coupling-link A B almost as strong as though it were a solid link.

As will be seen in Fig. 4, the width of the 70 recess *a* increases from the outer edge, *c*, to the inner around the curved end of the link, as does also the thickness of the tongue C. These parts are so constructed to prevent the tongue from becoming wedged in the recess 75 by dirt or sand, by the narrowing of the inner mouth of the recess by the spreading of the metal at that point, caused by the pressure of the link G upon it.

I am aware that prior to my invention links 80 have been made with an open side and a pivoted part with which to close it. I therefore do not claim such a combination, broadly; but

What I do claim as my invention, and desire to secure by Letters Patent, is— 85

In a coupling-link, the combination, with the body A, having a recess, *a*, formed therein which increases in width from the outer to the inner edge of the link, of the part B, hinged to the body A and having a tongue adapted 90 to be received in the said recess, substantially as and for the purpose specified.

BENJAMIN MORTON.
